UNITED STATES PATENT OFFICE

ALLAN S. BARROWS, OF LOS ANGELES, CALIFORNIA, ASSIGNOR TO THE YOUNGSTOWN STEEL DOOR CO., OF CLEVELAND, OHIO, A CORPORATION OF OHIO

CAR DOOR

Application filed April 23, 1928. Serial No. 272,038.

This invention relates to improvements in car doors.

As is well known to those skilled in the art, there are many railroad officials who prefer box car doors of the flush type on the grounds that the same provide for better protection against the weather and also better protection against theft or unauthorized access to the interior of the car. It is also well known to those skilled in the art that there is a general tendency to provide relatively large, wide door openings in box cars in order to increase the usefulness of the car for carrying different types of freight, particularly automobiles, which necessitate door openings of much greater width than the usual door opening of a box car. Coupled with the demand for wider door openings, which involve the use of auxiliary and main doors, and the desire on the part of many railroad officials for doors of the flush type, is the increasing demand for doors of the so-called sheet metal type which provide greater strength and cost appreciably less to maintain.

One object of my invention, therefore, is to provide a door arrangement particularly adapted for box cars, which will efficiently and economically meet all of the requisites hereinbefore indicated and, more specifically to provide a double, all metal, flush door arrangement.

Another object of my invention is to provide an improved sheet metal type of door particularly adapted for flush mounting wherein great strength and rigidity are obtained.

Another object of my invention is to provide a door arrangement particularly adapted for box cars wherein is employed an auxiliary door for obtaining greater width of door opening when required, in combination with a flush main door, with provisions for obtaining satisfactory sealing against weather and theft.

Other and more specific objects of my invention will more clearly appear from the description and claims hereinafter following.

In the drawings forming a part of this

specification, Fig. 1 is a side elevational view of a portion of a box car showing my improvements in connection therewith. Fig. 2 is a vertical, sectional view, parts being broken away, corresponding to the section line 2—2 of Fig. 1, the scale of Fig. 2 being appreciably greater than that of Fig. 1. Fig. 3 is a horizontal sectional view corresponding to the line 3—3 of Fig. 1, the scale being larger than that of Fig. 1 and parts being broken away in order to accommodate the figure on the sheet. Figs. 4 and 5 are detail, vertical sectional views corresponding to the section lines 4—4 and 5—5 of Fig. 3. And Figs. 6, 7 and 8 are views similar to Fig. 3 showing three modified forms of the forward edge of the auxiliary door.

In said drawings and referring first to the construction illustrated in Figs. 1 to 5, inclusive, the side wall of the car is indicated at 10 and the wide door opening thereof is defined by a threshold 11, lintel 12, and posts 13 and 14. Referring to Fig. 2, the threshold is shown protected by a sheet metal plate 15 and the threshold is recessed or rabbeted as indicated at 16 to permit of the flush positioning of the doors. Similarly, the posts 13 and 14 are protected by plate covers 17 and 18 and are also cut back or rabbeted as indicated at 19 and 20, to accommodate the vertical edges of the auxiliary and main doors, respectively, in the flush position. Along the top of the door opening, the side plate 21 is recessed or rabbeted, as indicated at 22, to accommodate the upper edges of the doors.

In carrying out my invention, two doors are employed, the auxiliary door being indicated generally by the reference character A and the main door by the reference character B. The detail construction of these doors will be described hereinafter. Each is mounted for flush positioning when over the door opening and to this end, a lower track 23 is employed, with which the door A is associated, and a corresponding upper track 24. These tracks, both of which are shown as comprised of Z-bars, have a straight section parallel with the side wall of the car, as best indicated in Fig. 3 and then an inwardly inclined portion, only one of which is indi-

cated at 123, for the lower track. Cooperable with the lower track are two hanger brackets 25 and 26, the former being rigidly secured to the forward edge of the auxiliary door A and the latter being pivotally associated with an operating shaft 27. The shaft 27 is rotatably mounted in suitable bearing brackets 28 along the rear edge of the door A and, at its upper end, is pivotally associated with a roller hanger bracket 29, the roller 30 of which rides upon the upper track 24. A second roller hanger bracket 31 is fixedly secured to the upper righthand corner of the door A, as best shown in Fig. 1. As indicated in Fig. 2, the hanger brackets are all so formed as to have a channel formation embracing the depending flanges of the bottom and top tracks respectively. The door B is correspondingly mounted on similar lower and upper tracks 223 and 224 and is provided with an upper fixed roller bracket 231, a fixed lower hanger bracket 225, an operating shaft 227, the latter having a hanger bracket 226 pivotally secured to its lower end, and a corresponding roller bracket 229 pivotally connected thereto at its upper end.

The means specifically shown and above described for supporting the doors and adapting the latter for flush positioning, may be varied without departure from my invention, the particular means shown being of well known form and being somewhat similar to those disclosed in my prior Patent 1,395,080, of October 25, 1921. As either door A or B approaches its closed position, the forward edge thereof will be moved inwardly to the flush position, due to the inclination of the tracks and, after the door has been advanced in a closing direction to the full extent, the operating shaft 27 or 227, as the case may be, is then actuated and the corresponding rear edge of the door forced inwardly to the flush position.

Referring to the main door B, the same is comprised principally of sheet metal and may be constituted of a single sheet or preferably made in three panels arranged horizontally one above the other. The metal sheets are provided with outwardly extended vertical edge corrugations 32 and 33 and between the latter and merging at their ends therewith are a plurality of horizontally extending and outwardly disposed corrugations 34. The vertical corrugations 32 and 33 are so positioned with respect to the front and rear edges of the door proper as to leave flat margins 35 and 36 respectively, the latter being somewhat wider than the former, in order to accommodate the bearing brackets for the operating shaft.

As shown best in Fig. 3, the vertical corrugations are braced by means of bridging strips 37 and 38, the former preferably having its outer end bent back so as to envelop the corresponding marginal portion 35, the

bridging strips being riveted or spot welded to the main sheets of the door on opposite sides of the vertical corrugations, respectively. Similarly, the top and bottom portions of the door B are strengthened by the top and bottom horizontal corrugations 134 and 234, respectively, over which are applied the corresponding bridging strips 334 and 434, respectively, as shown in Fig. 2, said bridging strips being also riveted or spot welded to the main sheets above and below their respective corrugations. In this manner, the door has flat marginal portions on all four edges and each marginal portion consists of two or more plies of sheet metal, thus providing a door of relatively great strength per unit of weight and one well adapted to resist stresses occurring in any direction. Further, it will be noted that the edges of the door, although consisting of two or more plies of metal, are of comparatively small over-all thickness, thus requiring only relatively shallow recessing or rabbeting of the members defining the door opening.

The auxiliary door A is constructed the same as the door B throughout the main body portion thereof and along the top, bottom and rear edges. A different construction is necessarily employed at the forward edge of the auxiliary door A, the details thereof being shown in Fig. 3. At its forward edge, the door A, instead of having a vertical corrugation with a flat marginal portion therebeyond, has the sheet inclined outwardly, as indicated at 39, to a plane preferably corresponding to the plane defined by the outermost portions of the strengthening corrugations or indentations. The sheet metal is then extended as indicated at 40 in a plane parallel with the main plane of the sheet. Secured to this forward edge portion of the auxiliary door and on the inner side thereof is a preferably rolled metal post 41. The latter is of generally channel cross section and has a long flange 42 on the side adjacent the door and a second flange 43 on the side remote from the door A. Intermediate the flanges 42 and 43 is the channel formation proper, the side sections thereof being indicated at 44 and the bottom section at 45. The latter is riveted, spot welded or otherwise rigidly secured to the flat marginal portion 40 of the door and the flange 41 is similarly rigidly secured to the sheets comprising the door A in the main plane of the latter and at points inwardly of the inclined section 39. As will be clear from an inspection of Fig. 3, an inwardly facing channel or recess is thus provided at the forward edge of the door A for the reception of the wood post or nailing post 46, which is suitably secured within the metal post 41 by any suitable means such as bolts and thus adapting the wood posts for renewal. The sheet metal sections 39 and 40 and the sections 42 and 44 of the post, together

constitute a tubular arrangement which imparts great strength and rigidity to the forward edge of the auxiliary door and one well adapted to resist either twisting or distortion from bending in any direction.

The outermost flange 43 is so extended as to overlap to an appreciable distance, the inner face of the forward edge of the main door B and together with an angular strip 47 which is riveted or otherwise secured to the post 41, constitutes a guide and recess for the multiple-ply forward edge of the door B and also constitutes a weather seal therefor. In this connection, it will be noted that the vertical edge corrugation 32 of the door B forms a baffle for rain or the like when the car is traveling toward the right, as viewed in Fig. 3 and, similarly, when the car is traveling to the left, the forward edge portion of the auxiliary door A, and more particularly the inclined portion 39, and metal post 41, provide a similar baffle, thus minimizing the amount of rain, snow or dirt that may be driven into the sealing joint between the two doors.

In addition to having the forward edge of the auxiliary door A moved inwardly through the tracks and hangers, it is important that said forward edge be rigidly held against lateral movement when the door occupies a closed position. For this purpose, I secure to the threshold, a plate 48 which is provided on the upper face thereof with a groove 49 having a relatively wide entrance opening or mouth 50, the groove then being inclined away from the side wall of the car for a considerable distance and having a final portion 51 which is parallel to the side wall of the car. Cooperable with the cam plate 48 is a casting 52 applied to the bottom of the wood post 46, said plate 52 having a rounded downwardly projecting stud 53 adapted to enter the groove 49, as best shown in Figs. 3 and 4.

Although I have described the details as applied to the lower end of the wood post 46, only, it will be understood that a duplicate arrangement is employed at the top thereof. With the arrangement described, as the forward edge of the door A approaches final position, the upper and lower studs 53 enter their respective cam slots 49 and the forward edge of the door is camed inwardly and then locked against lateral movement when the studs enter the straight portions 51 of the slots. It will also be understood that the slots 49 serve to positively limit the movement of the door A in a closing direction and further, when the rear edge of the door A is thrown inwardly to flush position, as shown in Fig. 3, the door A is positively locked against movement horizontally until the rear edge is again thrown out by the operating shaft.

Referring to the modification illustrated in Fig. 6, the main door is of the same con-

struction as that previously described. The auxiliary door has the sheet metal thereof outwardly inclined at its forward edge, as indicated at 139 and thence extends parallel to the side wall, as indicated at 140. A somewhat similar channel shaped metal post 141 is employed, riveted or spot welded to the flat marginal portion 140 of the door proper. In this instance, however, the flange 142 of the post is not extended over the inner face of the main portions of the sheets but is left in line therewith and an additional plate 60 is employed, the same being riveted or spot welded to the flat main portions of the sheets and also to the flange 142 of the channel post. The weather sealing strip 147 cooperates with the other extended flange 143 of the post, to provide the guide and weather seal. The arrangement of wood post 146 and locking means at the ends thereof are preferably the same as previously described in connection with the modification of Fig. 3.

Referring next to the modification shown in Fig. 7, the main door B remains the same and the auxiliary door has a similar outwardly sloping section 239 terminating in a flat marginal portion 240. In this construction, the post member is preferably comprised of two Z-section elements 241 and 341, the same having their flanges 245 and 345 overlapped and secured together and also secured to the flat marginal portion 240. The member 241 has one of its flanges elongated, as indicated at 242, the same being riveted or spot welded to the main flat portions of the door sheets.

In the modification shown in Fig. 8, the auxiliary door preferably has the same outwardly sloping section 339 and flat marginal portion 340, to which is rigidly secured a special section 70, the same having an elongated flange 71 overlying and rigidly secured to the main flat portions of the sheets; a transversely extending web 72 and a narrower outer flange 73, the latter being riveted or otherwise rigidly secured to the flat marginal portion 340. Said flange 73 is preferably flared outwardly, as indicated at 74, to form a guide for the forward edge of the main door. In this modification, another special rolled section is preferably employed, the same being indicated at 75 and being in the form of a cross in transverse section, two of the flanges—76 and 77 thereof, being secured to the member 70 at the corner thereof. A third flange 78 of the member 75 extends transversely inwardly and provides a backing for the wood post 346. The fourth flange 79 of said member 75 extends parallel with the side wall of the car and, in conjunction with said flange 73 forms a pocket or recess for the reception of the forward end of the main door B and also a weather seal at the meeting edges of the two doors.

I have herein shown and described what I now consider the preferred manner of carry-

ing out my invention, but the same is merely illustrative and I contemplate all changes and modifications that come within the scope of the claims appended hereto.

5 I claim:

1. In a member having a door opening defined in part by door posts, the combination with an auxiliary door; mounting means for moving said door to a flush position when opposite one portion of said door opening; a main door; means, independent of said first named means and auxiliary door, for moving said main door to a flush position when opposite the remaining portion of said door opening; and cooperable formations at the meeting edges of and rigid with respect thereto the two doors forming a weather seal when both doors are in flush position whereby the main door may be moved to open and closed position while the auxiliary door is in its closed position.

2. In a member having a door opening defined in part by door posts, the combination with an auxiliary door; mounting means for moving said door to a flush position when opposite one portion of said door opening; a main door; means, independent of said first named means and auxiliary door, for moving said main door to a flush position when opposite the remaining portion of said door opening; and combined guide and seat-forming means on the forward edge of and permanently affixed to the auxiliary door for the forward edge of the main door whereby the main door may be moved to open and closed position while the auxiliary door is in its closed position.

3. In a car having a door opening, the members of the car defining the opening being rabbeted for the reception of flush doors: the combination with an auxiliary sheet metal door; mounting means adapted to move said door to a flush position when opposite one portion of said door opening; a main sheet metal door; means, independent of said first named means and auxiliary door, for moving said main door to a flush position when opposite the remaining portion of said door opening; and cooperable formations at the meeting edges of and rigidly affixed to the two doors forming a weather seal when both doors are in flush position whereby the main door may be moved to open and closed position while the auxiliary door is in its closed position.

4. In a car having a door opening, the members of the car defining the opening being rabbeted for the reception of flush doors: the combination with an auxiliary sheet metal door; mounting means adapted to move said door to a flush position when opposite one portion of said door opening; a main sheet metal door; means, independent of said first named means and auxiliary door, for moving said main door to a flush position

when opposite the remaining portion of said door opening; and combined guide and seat-forming means on and forming an integral part of the forward edge of the auxiliary door for the forward edge of the main door whereby the main door may be moved to open and closed position while the auxiliary door is in its closed position.

5. In a box car having a side wall with a wide door opening therein, the combination with an auxiliary door mounted to move to a position to close part of said opening and to a position to uncover said part of the opening; of a horizontally slidable main door adapted to close the remainder of said opening said main door being movable to open position in a plane laterally outside of the car side wall; mounting and operating means for said main door arranged to move it laterally inward to flush position when brought opposite its closing position, said means being operable while the auxiliary door is in its operative closed position, and combined guide and seat-forming means on the forward edge of the auxiliary door for the forward edge of the main door.

6. In a box car having a side wall with a door opening therein, the combination with a sheet metal auxiliary door mounted to move to a position to close part of said opening and to a position to uncover said part of the opening; a horizontally slidable sheet metal main door adapted to close the remainder of said opening, said main door being movable to open position in a plane laterally outside of the car side wall; mounting and operating means for said main door arranged to move it laterally inward to flush position when brought opposite its closing position, said means being operable while the auxiliary door is in its operative closed position; and cooperable formations at the meeting edges of said doors forming a weather seal when both doors are in their closed positions.

7. As an article of manufacture, a door comprised principally of sheet metal, the metal of the sheets having outwardly disposed strengthening indentations and provided at the forward edge of the door with a marginal portion outwardly offset from the main plane of the door; and a metallic post having an offset therein and inner and outer sections, the latter being secured to the sheet metal in the main plane thereof and to said marginal portion, respectively.

8. As an article of manufacture, a fabricated door comprised principally of sheet metal and having strengthening indentations therein extended outwardly from the main plane of the door; a metal post at the forward edge of the door; and a nailing post secured to said metal post, the nailing post extending both inwardly and outwardly beyond the main plane of the sheet metal.

9. As an article of manufacture, a fabricated door composed chiefly of sheet metal and having strengthening indentations therein extended outwardly from the main plane of the door; a metal post at the forward edge of the door, said post being of channel formation with the channel facing inwardly; and a nailing post secured to said metal post within said channel, the nailing post extending both inwardly and outwardly beyond the main plane of the door.

10. As an article of manufacture, a fabricated sheet metal door having corrugations therein extended outwardly from the main plane of the door, said door being provided at the forward edge thereof with a metal post of channel formation with the channel opening inwardly of the door, said channel formation being disposed between said main plane of the door and the plane defined by the outermost portions of said corrugations.

11. As an article of manufacture, a fabricated sheet metal door having corrugations therein extended outwardly from the main plane of the door, said door being provided at the forward edge thereof with a metal post of channel formation, with the channel opening inwardly of the door, said channel formation being disposed between said main plane of the door and the plane defined by the outermost portions of said corrugations, said post having a forwardly extended flange substantially in the main plane of the door; and a combined guiding and weather sealing strip applied to said post on the forward side thereof and outwardly spaced from said flange.

12. As an article of manufacture, a car door having a main portion thereof comprised of sheet metal with the front marginal portion thereof outwardly offset from the main plane of the sheet; and a metal post structure at said forward edge of the door, said post structure being of generally channel formation with the channel opening to the inner side of the door and having flanges at each side of the channel opening extending forwardly and rearwardly of the door, the rearwardly extended flange being united to the main sheet portion rearwardly of said offset and the bottom of the channel section being secured to the offset portion of the main sheet.

In witness that I claim the foregoing I have hereunto subscribed my name this 27th day of March 1928.

ALLAN S. BARROWS.
